MICROPHONE WITH FUSE

Olof D. M. Guthe, Scarsdale, N. Y., and Oscar A. Shann, Short Hills, N. J., assignors to Bell Telephone Laboratories, Incorporated, New York, N. Y., a corporation of New York

Application September 1, 1945, Serial No. 613,984

1 Claim. (Cl. 179—122)

1

This invention relates to telephone transmitters and particularly to improvement in such transmitters to protect them against overloading.

Heretofore arrangements have been provided in connection with electrical circuits and associated telephone apparatus for protection against abnormally high voltages caused by overloading or acoustic shocks. One method was to incorporate shunting devices for such abnormal voltages as for example by inserting across a circuit an element having a negative temperature coefficient of resistance so that when such high voltages occurred in the circuit, they were by-passed by the circuits around the apparatus which they were designed to protect.

It is a feature of the present invention to provide a transmitter structure in which such protective elements are incorporated as permanent parts of the transmitter. The invention may be incorporated in the carbon button of a standard transmitter and may in this case take the form of a ring of a material having a negative temperature coefficient of resistance in which a metal diaphragm, in place of the usual mica diaphragm, is embedded. In the case of overloading or abnormal voltages in the line to which the transmitter is connected, this element will increase in temperature and thus quickly reduce its resistance and thereby protect the carbon granules from pitting by the momentary shunting of these excessive currents. Another form of this invention may be the substitution of such an element in place of a ceramic insulation element embedded in the transmitter where such an element forms part of the carbon chamber.

This invention has been illustrated in the accompanying drawings in which:

Fig. 1 shows a standard carbon button in which the applicants' invention has been incorporated;

Figs. 2 and 3 show modifications of the applicants' invention as applied in the button shown in Fig. 1; and

Fig. 4 shows a special type of transmitter in which the applicants' invention has been incorporated.

Referring now to the drawings, Fig. 1 shows a standard transmitter button comprising a casing 1 having a cavity, and an electrode, consisting of the usual metal disc 2 and carbon disc 3, inserted in the bottom of this cavity. The opposing electrode comprises a metal disc 4 and a carbon disc 5 and the space between the electrodes contains the usual carbon granules 6. To the metal disc 4 is applied a metal diaphragm 7 by means of a nut 8. This metal diaphragm has its outer rim embedded

in the element 10. This element is of the type having a negative temperature coefficient of resistance and is clamped over the cavity by means of a cap 11 screwed on casing 1. The disc 4 is secured to the usual diaphragm 12. The inside cylindrical surface of the cavity is insulated by a member 13. To the casing 1 is secured one terminating end 14 of the usual transmitter circuit while the other terminating end 15 of this circuit 10 is secured in the usual manner to the diaphragm for the passage of the talking current between the two electrodes for the operation of diaphragm 12 in accordance with voice current variations.

In the case of overloading of the circuits 14 and 15 by abnormal voltages, this element 10 would quickly increase its temperature and thus reduce its resistance and thereby permit these voltages to be shunted around the carbon discs and granules and thus protect them from pitting or other injuries. That is, this element may be so designed and possess such properties that for low voltages within the voice current level only a minute fraction of the current will be diverted thereby, whereas when abnormally high voltages occur much greater percentages of current will flow through this element to protect the carbon granules. Typical of suitable materials for the element 10 are those disclosed in Patents 2,258,646 granted October 14, 1941, to R. O. Griswold and 2,282,944 granted May 12, 1942, to E. F. Dearborn and G. L. Pearson.

In Fig. 2 the element 10 is shown as encased for protection against injury and to facilitate handling by a metal housing 17 of a U-shaped cross-section. In Fig. 3 this element 10 is shown in the form of a ring on the underside of the diaphragm 7 and these two elements insulated from the cap 11 by means of an insulation ring 20.

In Fig. 4 a different type of transmitter is shown, 40 in which the casing 22 is provided with an opening 23 closed at one end by means of a flexible, non-metallic disc 24 stiffened by a metal spider member 25. These members 24 and 25 are then secured between the usual diaphragm 26 and a 45 cup-shaped electrode 27 extending down into the opening in the casing 22. This opening is filled with carbon granules 30 and closed at the opposite end by an opposing electrode 32 having a contact ring 33. This latter electrode is secured 50 to the casing 22 by means of an insulation disc 34 having on its outer side a metallic ring 35 clamped down over the casing by means of the screw cap 36. The electrode 32 rests for this purpose against an element in the form of a ring 55 inserted in the opening and numbered 38. This

element 38 has a negative temperature coefficient of resistance and is substituted for the usual corresponding element in transmitters of this type of ceramic material. To insulate the carbon granules from this element 38 it may be coated on its inner surface with a ceramic or other insulation material. 39. This transmitter is otherwise identical with the construction disclosed in the Patent 2,042,832 to A. F. Bennett et al., of June 2, 1936. Circuit connections are made between the electrodes by a conductor 40 connected to ring 33 and a conductor 41 connected to cap 36. In this type of transmitter when subjected to overloading or abnormal voltages on the conductors 40 and 41, element 38 will quickly change its temperature and thus reduce its resistance and thereby shunt the excessive voltages around the carbon granules from the electrode 33 to the casing 22 to protect these granules against injury.

What is claimed is:

A telephone transmitter comprising a pair of line terminals, a casing having an opening therein, a ring element in said opening, said ring element having a negative coefficient of resistance, a first electrode adjacent said ring element in said

opening and electrically connected to one side of said ring element and to one of said terminals, a second electrode in said opening electrically connected to another side of said ring element and to the other of said terminals, comminuted resistance material between said electrodes, diaphragm means for vibrating said second electrode, and insulating means between said ring element and said resistance material.
